HAMMER HEAD WITH REMOVABLE TIP

Frank Guida, Norwood, Mass.

Application January 8, 1954, Serial No. 403,009

2 Claims. (Cl. 145—36)

2

to the body 14, the bore 16 is widened as at 44 for a portion of its depth, as indicated in Figures 5 and 6, these opposed widened areas being shaped to provide just enough clearance for the bulges 40 and 42 and forming shallow longitudinal channels extending in just far enough to permit the shoulder 22 to seat on the face 24. In the wall of the bore 16 are two shallow arcuate opposed recesses 46, these recesses having an axial dimension equal to or slightly greater than the wire diameter of the spring 30. The recesses 46 are angularly spaced 90° from the widened areas 44, as indicated in Figures 4, 6 and 9, and are at the inner end of the widened areas where they form with the widened areas a set of four symmetrically arranged, radial recesses. When a tip 12 is applied to the body 14, the stem 18 is inserted into the bore 14, the bulges 40 and 42 of the spring 30 entering the widened area 44. The stem is moved in until the shoulder 22 engages the face 24, whereupon the spring 30 is opposite the recesses 46. The tip 12 is then turned 90° from the position shown in Figure 9 to that shown in Figure 4. Since the spring 30 is anchored to the stem 18 by the engagement of its inturned end 32 in the hole 34, the spring must turn with the tip 12. As the tip turns, the bulges 40 and 42 are sprung inward as they engage and ride over the points 50 in the wall of the bore, then spring outward to enter the recesses 46, thus locking the tip 12 in place. To remove the tip, it is rotated a quarter turn from the position shown in Figure 4 to that shown in Figure 9, whereupon it can readily be withdrawn from the bore 16. Since considerable force, depending on the characteristics of the spring 30, is required to turn the tip 12, there is no danger of its working loose or coming off the head accidentally.

I claim:

1. A hammer head having a body portion and a removable tip secured thereto, said body portion having a short bore with shallow opposed longitudinal channels extending in from the outer end thereof and radial recesses spaced inward from the outer end thereof and angularly spaced from said channels, said head having a stem adapted to enter said bore, said stem having a circumferential groove and a spring member seated in said groove with portions bulging out of the groove to enter said channels and recesses, whereby rotative movement of said tip on said body portion locks said tip on said body portion and unlocks said tip for axial removal from said body portion.

2. A hammer head having a body portion and a removable tip secured thereto, said body portion having a short bore with shallow arcuate recesses in its wall, some of which recesses open in from the end of said body portion and some are undercut, said tip having a stem adapted to enter said bore, said stem having a circumferential groove, and a spring member mounted on said stem with portions thereof disposed in said groove and other portions bulging from said groove to engage alternatively in said open recesses or said undercut recesses according to the angular position of the tip relative to the body of the hammer whereby to lock or release said tip on said body.
